United States Patent Office

Des. 208,991
Patented Oct. 24, 1967

208,991

GARDEN TOOL

Howard A. Anderson, Pittsburgh, Pa., and Henry J. Rosendall, Grand Rapids, Mich., assignors to Bissell Inc., Grand Rapids, Mich., a corporation of Michigan

Filed Aug. 24, 1966, Ser. No. 3,571

Term of patent 14 years

(Cl. D35—2)

FIG. 1.

FIG. 2.

FIG. 3.

FIG. 4.

FIGURE 1 is a top plan view of a garden tool, showing the new design;

FIG. 2 is a side elevation thereof;

FIG. 3 is an end view thereof, taken on line 3—3 of FIG. 2; and

FIG. 4 is a bottom plan view thereof.

We claim:

The ornamental design for a garden tool, substantially as shown and described.
